Primary Examiner — Khawaja Anwar*Assistant Examiner* — Taylor O Mortorff(74) *Attorney, Agent, or Firm* — Lando & Anastasi, LLP(57) **CLAIM**

The ornamental design for a broom handle, as shown and described.

DESCRIPTION

FIG. 1 is an environmental perspective view showing broken-line environmental items with the broom handle according to a first embodiment;

FIG. 2 an upper perspective view thereof;

FIG. 3 is a lower perspective view thereof;

FIG. 4 is a front view thereof, the front view being the same as the rear view thereof, the left side elevation view thereof, and the right side elevation view thereof;

FIG. 5 is a top view thereof;

FIG. 6 is a bottom view thereof; and,

FIG. 7 is a sectional view thereof along the line 7-7 in FIG. 5.

The broken lines show environmental items and portions of the broom handle that form no part of the claimed design.

1 Claim, 6 Drawing Sheets(56)
